ICE-MAKING MACHINE

Edward C. Walsh, Oak Ridge, Tenn., assignor to
 Flakice Corporation, Brooklyn, N. Y., a corpora-
 tion of Delaware

Application April 14, 1948, Serial No. 20,942

8 Claims. (Cl. 62—107)

1

This invention relates to improvements in machines for producing flaked or chipped ice or flakes of other similar frozen or congealed materials of comparable consistency and other related properties.

Machines capable of effectively producing ice in this form are highly in demand due to the fact that there is a great demand for this type of ice and furthermore, its manufacture in this form is considerably cheaper than to manufacture it in the form of blocks, due to the lesser amount of refrigeration requirements.

My invention is particularly an improvement in that type of chipped ice manufacturing machine wherein the ice is frozen on a surface and then is caused to be sheared from the surface or otherwise freed from the surface by having the bond between the ice and the freezing surface broken.

The primary object of my invention is to provide an improved machine of the character described wherein the arrangement for shearing off the ice, that is, freeing it from the freezing surface is very effective. It is an object of the invention to achieve this characteristic while at the same time providing a machine which is positive in action throughout its operation, which is as compact as possible and which has low power requirements, especially for effecting the ice removing action. Freeing the ice from the freezing surface has in the past been one of the major difficulties, since the ice adheres to the surface quite tenaciously, and it has been found difficult to remove it without utilization of large amounts of power and without resorting to mechanisms susceptible to failure and rapid deterioration under conditions of continual service.

Another object of my invention is to provide a machine of the character described, which is of simple construction, making it easy to repair and replace parts.

Another object of the invention is to provide a machine of the class described wherein the ice freezing surface is in the form of a plate having the characteristic that it can be bulged or bowed out of a plane in a manner that its curvature can be changed from concave to convex, the change in curvature of the plate being such as to cause ice frozen to the plate to be sheared off when it is bulged or buckled from one side of said plane to the other.

Another object of the invention is to provide a machine as in the foregoing object wherein the plate or freezing surface is associated with a freezing or cooling unit having a curved surface

2

conforming to the bulged surface of the freezing plate.

Another object of the invention is to provide a machine as in the foregoing objects wherein the freezing plate or surface forms a side wall of a pressure chamber in which the freezing unit is located with pumping means for changing the pressure in the pressure chamber to cause the freezing plate to be alternately dished or bulged against the freezing unit, and dished or bulged away from the freezing unit to cause the ice to be sheared off therefrom.

Another object of the invention is to provide a machine as in the foregoing wherein the ice freezing surface is in the form of a snap disc having associated therewith a freezing unit having a surface shaped to conform to the disc when the disc is in one of its over-center positions.

Another object of the invention is to provide a machine as in the foregoing object wherein a timed mechanical actuating device is provided for periodically snapping the disc over center.

Another object of the invention is to provide a machine of the class described wherein the freezing surface forms one side wall of an evaporator unit of a refrigerating system and has the characteristic of being operable to have its shape or configuration changed from concave to convex as a result of the changes in pressure within the evaporator unit.

Another object of the invention is to provide a machine as in the foregoing object wherein a connection is provided to admit high pressure refrigerant from the system into the evaporator to increase the pressure therein, and an automatic timing device controlling said connection so as to periodically change the pressure in the evaporator in a manner to cause the ice to be freed from the freezing surface.

Further objects and numerous of the advantages of my invention will become apparent from the following detailed description and annexed drawings wherein

Figure 1 is a cross-sectional view of a form of my invention wherein the ice freezing surface is a snap disc.

Figure 2 is a sectional view of Figure 1 taken along the line 2—2 of Figure 1.

Figure 3 is a cross-sectional view of a second form of my invention utilizing different types of freezing surfaces.

Figure 4 is a sectional view of the machine of Figure 3 taken along the line 4—4.

Figure 5 is a cross-sectional view of a third

form of my invention wherein the freezing surface forms one side wall of an evaporator unit.

Figure 6 is a sectional view taken along the line 6—6 of Figure 5.

From the foregoing it will be understood that my invention comprehends broadly the concept of freezing water or other matter, on a surface which is capable of having its shape or configuration changed so that upon the changing of such configuration after the ice has been frozen thereon, it is caused to be sheared off as a result of the changing shape. The invention comprehends broadly a freezing surface which can be buckled, deformed, or bowed outwardly from a plane and then sprung or buckled again. Refrigeration or cooling may be applied, preferably to one side of the surface in various ways and certain preferred manners of so doing will be shown. The invention comprehends the concept of providing means operative to cause the bulging, deforming, or dishing of the freezing surface necessary to cause the ice to be sheared therefrom. This operation may be performed by mechanical means or other equivalent means, such as pneumatic or hydraulic cylinders or by applying gaseous pressure to the freezing surface itself. The invention comprehends a freezing surface formed of a metal which can be distended or a flexible material which can be distended or expanded.

Referring more specifically to the drawings in Figure 1, numeral 9 represents an insulated compartment within which is disposed the ice freezing mechanism and the compartment having doors 8 through which the accumulated ice can be removed. Numeral 12 designates a snap disc which is a device known in the art and it is adapted to snap or buckle from one side to the other of a central plane, as is well known in the art. The disc 12 is mounted at its periphery in ring shaped mountings as indicated at 13 which are of slightly larger diameter to allow for the increase in circumference of the disc as it passes over its dead center position. Numeral 15 designates the evaporator or cooling unit of a refrigeration system, shown diagrammatically at 17. The cooling unit 15 may employ vaporizable refrigerants as in a compression system or the refrigerant may be brine cooled below freezing temperature. The cooling unit 15 is ring shaped as shown and its upper surface is shaped to conform to the surface of the under side of the disc 12 and when the disc is in its lower position, it lies flat against the unit 15. Water supply nozzles or sprays 22 are provided around the periphery of the disc from a supply not shown for providing water which drains onto the disc and which is to be frozen thereon. The disc has a group of openings arranged in a circle, as shown at 21, to allow excess water to drain off the disc near its central portion and this excess water is collected in the trough 27 and drained off through a drain tube 28.

A vertical stem 23 is attached to the central portion of disc 12 by means of discs 24 and 25 on opposite sides of the disc 12, and this stem can be reciprocated as will be described, to snap the disc 12 from one of its positions to the other. At its lower end the stem 25 carries a disc 30 and it has a coil spring 26 surrounding it. The spring bears against this disc and against an abutment 22, normally urging the stem in a downward direction. The disc 30 forms a follower for a cam 29 having a single dwell and it is driven by a motor 35. The motor 35, is con-

trolled by an electric timer 36 which energizes the motor at periodic intervals so as to rotate the cam 29 through one revolution for moving the stem 23 and consequently the disc 12 upwardly to its opposite position and allowing it to come down again under the influence of the spring 26.

In operation, the unit 15 is at below freezing temperature and as the water flows onto the disc 12, a film of ice is formed thereon in a short period of time. Upon energization of motor 35 the disc 12 is snapped to its upper position as described, the change in shape and conformation of the disc necessarily causing the film of ice to be completely sheared off the disc. The film of ice becomes fractured in numerous places and slides off the disc around its periphery and drops to the bottom of the compartment 9 where it can be removed through the doors 8.

Various other equivalent mechanisms may be provided to actuate the disc 12 as originally described, such as a pneumatic or hydraulic cylinder or other means. The timer 36 may be of a known type, set to actuate the motor 35 at predetermined intervals to cause the ice removing action to be performed substantially as soon as the film of ice has been frozen on the disc 12.

Various modifications are clearly within the realm of the invention. For instance, the snap disc might have a relatively large central opening with the sprays more centrally located so as to freeze the ice film with the disc in its upper position. The sheared off ice would then be collected after passing through the central opening. While only a single disc is shown, multiple discs might be employed and they might be large or small, as desired. While a metal disc is preferred, other material might conceivably be employed.

Referring to Figure 3 of the drawings, a similar insulated compartment 37 is shown having there-in an evaporator or freezer unit 38 connected by pipes 42 and 43 to a refrigerating or cooling system, designated generally at 40. The refrigerating unit 38 has a dished or concave surface as shown at 39 and a freezing surface or plate 48 is adjacent this face of the refrigerating unit and is adapted and formed to be operable to be dished or bowed so as to lie flat against the curved surface of the unit 38. The freezing surface 48 forms one side wall of a pressure chamber 45 within which the unit 38 is disposed. Surface or plate 48 is attached to the chamber 45 by having its edge portions engaging in a groove in the mounting flange 49 and it may be welded or otherwise sealed thereto. The plate 48 and chamber 45 are shown as being substantially square in Figure 4, but it is to be understood that other shapes may be employed. The plate 48 may be a strip, for example, mounted only at two of its opposite sides, and bowed or capable of being bowed or bulged from one extreme position to another. Figure 3 shows the plate 48 lying flat against the curved surface of unit 38 and its other position is shown in broken lines. The curved surface 39 of the unit 38 has transverse grooves or depressions 46 therein and pressure within the chamber 45 may pass into these grooves at their ends and when the pressure is sufficiently high the plate 48 will be dished or bulged in the opposite direction to cause the film of ice frozen thereon to be sheared off as in the previous embodiment.

Nozzles or sprays 44 are provided to spray water on the upper part of the plate 38 to be frozen thereon in the form of a film. The plate 48 is

of course, made of a good heat conducting material so that heat is readily conducted through the plate and to unit 38.

At the lower part of the plate 48 and chamber 45 is a trough 63 to collect the excess water flowing down the plate 48 and this water may be drained off through the tube 64.

Numeral 53 designates an air pump which may be driven by any convenient means, and connected through pipes 55 and 56 and through a four-way valve 54 to the interior of chamber 45. The four-way valve 54 has a rotor 66 as shown, having two positions such that the interior of the chamber 45 can be connected to either the suction or discharge of the air pump 53 (by rotating member 66 through 90°). When the interior of chamber 45 is connected to the suction of pump 53, the pressure within the chamber is reduced and atmospheric pressure on the exterior of the chamber bows the plate 48 and urges it against the curved face of the unit 38 so as to be in good thermal contact therewith. When the discharge of the pump 53 is connected to the interior of the chamber 45, the pressure therein is increased substantially above atmospheric pressure and this pressure acting within the grooves 46 bows or dishes the plate 48 in the opposite direction to its dotted line position, and the change in shape and conformation of the plate causes the ice to be sheared off therefrom and to be fractured in numerous places. The ice drops down and collects in the lower part of the compartment 37 and may be removed through the door 65.

The rotor of the four-way valve 54 is connected to an automatic periodic timing device 61 with the periodic intervals determined in advance. It reverses the position of valve 54 and accordingly, the connections to the pressure chamber 45, so as to effect the ice removal action as described.

The valve 54 is kept in position such that the discharge of pump 53 is into chamber 45 for a short interval long enough to allow the pressure to be built up in the chamber sufficiently to bow plate 48 to its outward position. Upon the position of the valve 54 being again changed, the pressure in chamber 45 is reduced and plate 48 again assumes the position shown in the drawing. The evacuation of the air from within chamber 45 serves to inhibit condensation of moisture therewithin and consequent freezing of member 48 to the surface of unit 38. The evacuation also acts as an insulating blanket for unit 38 so that the refrigerating effect is devoted entirely to cooling the member 48 and freezing the film of ice thereon.

The member 48 may be a relatively thin sheet of material capable of being bowed as described, and it is within the comprehension of the invention that other flexible or deformable material be used such as a rubber diaphragm or sheet.

The timing device 61 may embody a motor drive for the valve 54 or there may be an electro-magnetic connection for changing the position of the valve. Such devices are well-known in the art and therefore need not be described in detail.

Referring to Figure 5 of the drawings, the insulated compartment is shown at 67, having therewithin an evaporator unit 69 forming part of a compression type refrigeration system designated generally at 73. The system comprises a compressor 75 driven by a motor 82, a condenser 76 having a receiver 81, all connected in refrigerant flow relationship with the evaporator unit 69 as described. An expansion valve 77 of a conventional type is provided in the refrigerant sup-

ply line 84 and the suction line 83 may have a check valve 90 therein as shown. The evaporator unit 69 is of relatively small depth and it is rectangular in cross section as shown in Figure 6, but it may have various other shapes. The evaporator unit 69 has one side wall 71 formed of a relatively thin material capable of being dished or bowed from a concave position as shown, to a convex, as shown in broken lines. The side wall or plate 71 is attached to the rigid portion of evaporator unit by welding or by other means of sealing.

Water sprays 85 are provided as in previous embodiments and trough 86 having drain pipe 87 is provided to catch the excess water draining off the plate 71. Accumulated ice may be removed through the removal door 91.

In the present embodiment, a bypass line 78 is provided from the upper part of the condenser 76 to the evaporator unit and in this line is a solenoid valve 79 controlled by an electric timing device 80. The timing device 80 is set to periodically open the valve 79 at intervals so as to admit high pressure refrigerant gas into the evaporator 69. This high pressure refrigerant bows the plate or side wall 71 outward causing the ice to be sheared off therefrom as in previous embodiments. The valve 79 is kept open only long enough to effect the ice removal action and normal refrigeration is then resumed. The usual conventional controls may be provided for the compressor motor 82 as desired.

From the foregoing, those skilled in the art will observe that I have provided a very convenient, simple and effective machine for achieving the desired purpose of freezing a film of ice on a surface and then causing it to be sheared off and broken up into pieces and collected.

Various modifications and alternatives may be practiced by those skilled in the art and various equivalent devices may be substituted for different parts. It is intended that all such variations and modifications and all proper equivalents as to the individual parts and combinations thereof will fall within the scope of the claims appended hereto, it being intended to claim the invention as broadly as the state of the art will allow.

Having thus described my invention, I claim:

1. In a machine of the character described, in combination, means forming a piece of material capable of being bowed outwardly from a plane, means for applying refrigeration to one side of said material, means arranged to apply water onto said material and freeze thereon and a mechanism arranged and positioned to apply a force against said material at a point spaced from its supports so as to oppositely bow said material outwardly from a plane and to thereby shear said ice off and to separate the ice from said material, said piece of material forming one side of a pressure chamber and pumping means capable of changing the pressure in said chamber from below to above atmospheric, the refrigeration applying means being within the pressure chamber.

2. The structure of claim 1 including a timing device controlling the pumping means to effect raising of the pressure in the chamber periodically for short intervals.

3. In apparatus of the character described, in combination a member having a deformable portion adapted to be dished, refrigeration means having a cooling portion shaped to conform to the convex side of the said dished portion, means for

applying water to the concave side of the dished portion to be frozen, and means associated with the dished portion for applying a force substantially normal to the surface thereof for causing the dished portion to buckle and to be dished in the opposite direction so as to cause the ice to be freed therefrom.

4. The structure of claim 3 wherein the said member and the said cooling portion have relative conformations to permit access of fluid under pressure between them to effect the opposite dishing of the said member.

5. In the art of congealing liquids, the steps of, cooling a freezing zone, withdrawing air from the vicinity of said zone thereby to produce a partial vacuum condition, utilizing said partial vacuum condition to draw a freezing surface into said freezing zone, and changing said partial vacuum condition to a pressure condition whereby said freezing surface is moved from said zone and flexed so as to remove ice from said freezing surface.

6. In ice making apparatus, the combination of, a rigid evaporator presenting a rigid refrigerated surface, a casing surrounding said evaporator and including a flexible member positioned adjacent said refrigerated surface and adapted to move to and from intimate contact therewith, and pressure changing means which is adapted to change the pressure condition along said refrigerated surface and thereby to move said member to said intimate contact during a congealing operation and to move said member away from said refrigerated surface for the harvesting operation.

7. In a machine of the character described, in combination, means forming a piece of material capable of being bowed outwardly from a substantially flat plane surface and forming a side wall of a pressure chamber, means for applying refrigeration to one side of said material, water circulating means arranged to spray water on said material whereby it freezes and forms ice

thereon, and air pumping means connected to said chamber to change the pressure therein in a manner to apply a force against said material at a point spaced from its supports so as to oppositely bow said material outwardly from said plane and to thereby shear the ice free and to separate the ice from said material.

8. In apparatus of the character described, in combination, a unit having a deformable portion which is dished and has a peripheral zone and includes means supporting said deformable portion at said peripheral zone whereby said deformable portion has its central portion adapted to move from its dished position wherein it presents a concave freezing surface to a deflected position wherein said freezing surface is substantially convex, refrigeration means to cool said deformable portion and form ice thereon along the convex side of said deformable portion when it is in said dished position, means for supplying liquid to be frozen to the concave side of said deformable portion, and means associated with said dished deformable portion for applying a force substantially normal to the surface thereof causing said dished deformable portion to move outwardly from its dished position to said deflected position to remove the ice therefrom.

EDWARD C. WALSH.
